UNITED STATES PATENT OFFICE.

ADAM HENRY PRENZEL, OF HALIFAX, PENNSYLVANIA.

STAPLING MACHINE.

Application filed August 21, 1922. Serial No. 583,322.

To all whom it may concern:

Be it known that I, ADAM H. PRENZEL, a citizen of the United States, and a resident of Halifax, in the county of Dauphin and State of Pennsylvania, have invented certain new and useful Improvements in Stapling Machines, of which the following is a specification.

My invention relates to improvements in stapling machines, and it consists of the constructions, combinations and mode of operation herein described and claimed.

An object of the invention is to provide a stapling machine with means to form pleats, folds or puckers to take up the slack leather as the staples are inserted.

A further object of the invention is to provide a stapling machine with means to draw the leather down tight over the last as the staples are inserted around the toe.

A further object of the invention is to provide a fold controller and side wipers which cooperate with fingers to form folds or puckers during the operation of the stapling machine in which they are embodied.

A further object of the invention is to provide a fold controller, side wipers and fingers coacting with the staple guide of a stapling machine, to grip and stretch the upper and lining before the staple is driven, thereby preventing the upper and lining from receding and thus tending to straighten out the sole flange to which they are stapled.

A further object of the invention is to provide means for adjusting the aforesaid fingers either forwardly, to lengthen the fold, or upwardly to make a larger fold and thus draw the work up closer around the toe.

Other objects and advantages will appear in the following specification, reference being had to the accompanying drawings, in which:

Fig. 1 is an elevation of the right side of a stapling machine embodying the improved fold-forming mechanism.

Fig. 2 is a side elevation of the left side of the same machine,

Fig. 3 is a detail sectional view (parts in elevation) corresponding in position to Fig. 1 and showing the driving head and rocker in what might be termed the normal position, the flange and upper structure of a shoe being respectively positioned under and above the fingers in readiness for the stapling operation.

Fig. 4 is a similar view showing the rocker and driving head brought down in the first step of the operation, the fold controller, side wipers, staple guide and fingers all aiding in drawing the leather tight and forming the folds.

Fig. 5 is a view similar to Fig. 4, illustrating the second step of the operation wherein the staple is driven by means of the driving arm.

Fig. 6 is a detail perspective view of a partly finished shoe showing how the folds are formed as the staples are driven, and also illustrating the ample selvage left between the line of the staples and the edge of the last for subsequent sewing.

Fig. 7 is a detail front elevation of the machine in Fig. 1.

Fig. 8 is a detail plan view of the stapling bracket, showing the lasting fingers in place.

Fig. 9 is a detail section taken on the line 9—9 of Fig. 3 and illustrating the disposition of the parts in the normal position of the machine.

Fig. 10 is a section on the line 10—10 of Fig. 4 showing how the folds are formed in the second step of the operation.

Fig. 11 is a detail elevation (somewhat exaggerated) illustrating the imprints left by the lasting fingers, side wipers, staple guide and fold controller when the driving head is brought down into the position in Fig. 5.

Fig. 12 is a detail perspective view of a portion of the stapling machine, illustrating the side wipers and fold controller removed, and showing the lasting fingers in position.

Fig. 13 is a detail perspective view of the front of the side wiper and fold controller support.

Fig. 14 is a similar view illustrating said support from the rear, and

Fig. 15 is a detail perspective view illustrating the finished shoe in so far as the 5 stapling and sewing are concerned.

This invention is one of a series of three which relate to applying the upper leather and lining to the sole of a shoe. The second invention (disclosed in Patent 1,489,966, 10 granted to me April 8, 1924) comprises an attachment to the machine in Fig. 1 and in substitution for the stapling bracket shown therein, for the purpose of inserting staples around the heel seat, as shown in Fig. 15. The third invention (also disclosed in my 15 Patent 1,500,527 of July 8, 1924) consists of the peculiar method which is followed in applying the upper leather and lining to the flange of the shoe sole.

Structure which is not a part of the invention but which is necessary in combination with the fold-forming mechanism which is the invention, briefly described, comprises the standard 1 which is preferably hollow so that the connecting rod 2 may be extended therethrough down to the floor where it is attached to a treadle (not shown). The upper end of the connecting rod 2 is pivotally joined at 3 to an actuating 25 link 4 which, in turn, is pivoted at 5, to a dog 6 which has a pivotal mounting at 7 to a portion of the frame 8 which is fixed at 9 to a table 10 on top of the standard.

A rocker arm 11, pivoted at 12 to the 30 actuating link 4 and guided between the frame 8 and a lug 13, depresses the rocker 14 through its pivotal connection 15 therewith upon each operation of the connecting rod 2, and necessarily of the treadle (not shown) to which it is joined at the bottom. The rocker 14 is pivoted at 16 to the frame. The driving arm 17 is pivoted at 18 to a link 19, which in turn is pivoted at 20 to the frame. A depression of the treadle to 35 which the connection rod 2 is joined, causes the depression of the rocker 14, and simultaneously therewith causes the dis-engagement of the dog 6 from the clutch 21 and the heel 22 from the recess 23 in the hub 50 of an eccentric 24. As the shaft 25 revolves continuously while the machine is in operation, the disengagement of the clutch 21 causes the eccentric to be locked to the shaft so that the eccentric arm 26 rocks the driving arm 17 on its pivot 18 and causes the driver 27 to insert a staple into the shoe leather which is in the proper place. The 55 engagement of the clutch 21 with the continuously rotating part from which driving motion is derived, is severed when one revolution is made and the dog is again reached. It is believed that the above 60 description (although brief) is sufficient to enable the reader to gain a general idea of

the operation of the stapling machine, and 65 attention is now directed to the fold forming mechanism which, in combination with the foregoing stapling machine, constitutes the invention. The purpose of the invention is to form a fold 28 (Fig. 6) at the edge of 70 the upper leather 29 and lining 30 and at each side of a staple 31 as the latter is driven in place on the flange 32 of the furrow 33 by the driver 27. Again, it is a purpose of the invention to draw down the upper 75 leather 29 and lining 30 smoothly around the toe of the last 34, not only for the purpose of making a shoe of very neat appearance, but also to properly stretch the upper leather and lining and further to provide an ample 80 selvage 35 between the line of staples 31 and the edge 36 of the last so that there may be plenty of room for inserting the line of stitching 37 in Fig. 15.

Consider Fig. 3. The stapling bracket 38 85 is detachable from the frame 8 of the machine, to which it is normally secured by means of a bolt 39. The heel 40 of the bracket 38 has a rectangular recess 41 in which the ends of the staples 42 are upset 90 when driven by the driver 27 as in Fig. 5. Plates 43 carry the lasting fingers 44 which are spaced apart sufficiently to admit the staple guide 45 when the driver 27 is depressed to drive a staple. Each lasting finger terminates in a flattened end or plate 46 through which it is mounted on the inside of each of the plates 43 by means of bolts 47. These bolts extend through slots 48 in the plates 43, the slots enabling longitudinal adjustment of the lasting fingers so as to enable lengthening the pleats 28 (Fig. 6). The plates 43 are adjustable vertically by means of bolts 49 and slots 50 so as to enable making larger folds and thus draw 105 the work up closer around the toe of the last.

A stem 51 passing transversely of the lasting fingers and having threaded ends to receive the adjusting nuts 52 and 53 (Fig. 110 8), carries springs 54 and 55 which respectively bear on the outer sides of the lasting fingers and impart a certain resiliency to the fingers which is valuable in letting the fingers give when the staple guide 45 imposes upon an upper structure which might be thicker than others. A supporting bridge 56, secured at 57, so as to occupy a desired position beneath the fingers, lends support to the fingers and takes from them 115 strains which might otherwise be injurious.

The type of shoe which this stapling machine is intended to handle is more particularly the type disclosed in my United States Letter Patents granted July 8, 1924, although the use of the machine is not confined solely to stapling shoes of this type. Upon presenting the shoe to the stapling 125

machine the flange 32 is inserted beneath the lasting fingers 44, the upper leather 29 and lining 30 being placed above.

Attention is next directed to Fig. 4 which shows the first step in the operation of the machine. The operator depresses the treadle (not shown) and consequently causes the rocker 14 to swing down on its pivot 16 (Fig. 1) so that the staple guide 45 is brought down and presses the upper structure in between the ends of the lasting fingers 44. Simultaneous with this act (and necessarily so because they are mounted upon the same structure), the side wipers 58, 59 and the fold controller 60 are brought down upon the shoe upper structure so that the upper 29 and lining 30 are drawn tight over the toe of the last 34 (Fig. 4) by the fold controller and also are drawn tightly over the ends of the lasting fingers 44 by the side wipers 58, 59 (Fig. 10).

If the imprints of the staple guide 45, side wipers and fold controller were deep enough, they would appear as in Fig. 11. As stated above, this view is an exaggerated illustration and in actual practice these imprints do not appear on the leather. However, by considering the imprints, shown in Fig. 11, the reader can readily conceive how the leather is engaged and gripped in a number of places to effectively draw down the leather over the toe of the last and at the same time draw it down over the ends of the lasting fingers. The result of driving a number of staples is to produce a series of folds 28 (Fig. 6) which take up the slack leather and enable the production of a finely finished shoe when completed.

A support 61 carries both the side wipers and fold controller. Screws 62 (Figs. 7, 13 and 14) secure the support upon the driving head of the rocker 14, both the support and the driving head having suitable apertures (Figs. 12 and 13) into which the screws pass. For purposes of perpendicular adjustment, the side wipers are slotted at 63 and the fold controller is slotted at 64. Screws 65 and 66 respectively pass through the slots and enable tightening the various parts in the desired position.

However, the screws 65 of the side wipers also pass through horizontal slots 67 in the sides of the support 61 and thence directly into the driving head. Upon unloosening the side screws 65 the support 61 can be adjusted outwardly in respect to the driving head so as to advance the fold controller 60 in respect to the ends of the lasting fingers 44 as much as desired. The screws 66 pass directly into the front of the support 61 and have no connection with the driving head of the machine.

In order that no damage may befall the leather when the driving head is brought down as in Fig. 4, the ends of the side wipers 58, 59 are rounded. This rounding may consist of merely bending the ends over upon themselves as shown in Figs. 13 and 14, or it may consist of other arrangements deriving the same effect. It is necessary to bend the lower end of the fold controller 60 inwardly so as to come closely to the ends of the lasting fingers. The lower end of the fold controller is flared as shown, so as to present an ample gripping surface or edge.

The stapling mechanism of the machine is so designed that the staples 31 are driven far enough away from the edge 36 of the last (Fig. 3) to leave sufficient space for the placing of the stitches 37. According to the method of making shoes disclosed in the Patent 1,500,527 mentioned above, the crease at the base of the flange 32 forms a guide for the needle during sewing. As it would obviously be undesirable to have the staples driven too close to this crease, it is evident that the function of the machine in driving the staples well beyond the selvage 35 (Fig. 6) well adapts this machine to carry out the aforesaid method. It is to be observed in Fig. 15 that the upper leather and lining are affixed around the heel seat by means of staples. This particular result cannot be accomplished with the mechanism as it is now arranged, it being necessary to remove the side wiper and fold controller support 61 and also to substitute another style of stapling bracket 38. This particular bracket is the subject matter of another application, and a description thereof would find no place here.

Attention is directed to Fig. 5 which illustrates an act which immediately follows the act in Fig. 4. The staple 42 is driven immediately after the staple guide 45, side wipers 58, 59 and pleat controller 60 have performed their functions of drawing the leather down tightly over the ends of the lasting fingers and over the end of the toe of the last. As explained above, a depression of the treadle not only depresses the rocker 14 but also sets the shaft 25 in motion so that the driving arm 17 (Fig. 1) is rocked on its pivot 18 and the driver 27 is caused to drive a staple. This is the act illustrated in Fig. 5, wherein the driving arm 17 and driver 27 are shown depressed.

While the construction and arrangement of the improved stapling machine as herein described and claimed, is that of a generally preferred form, obviously modifications and changes may be made without departing from the spirit of the invention or the scope of the claims.

I claim:—

1. A stapling machine comprising means to support a portion of a sole and a last which also carries an upper leather and lining, means to separate the sole portion from

the upper leather and lining, stapling mechanism forming part of the machine and being adapted to be brought down upon the upper leather and lining to drive a staple therethrough into the sole portion, and means movable with the stapling mechanism upon being thus brought down to form the peripheral portions of the upper leather and lining into folds, to take up the slack and at the same time draw them tightly over the toe of the last while the staple is driven.

2. A stapling machine comprising means to support the peripheral portion of a shoe sole and a last which also carries an upper and lining, spaced apart means which is inserted between the sole and said upper and lining when placed in position upon said support, stapling mechanism including a staple guide which is adapted to enter between said spaced apart means for the stapling operation and form a part of two folds, and means associated with said staple guide to engage the upper and lining on the outside of said spaced apart means to complete the formation of said folds before the staple is driven.

3. A stapling machine comprising means to support the peripheral portion of a shoe sole and a last which also carries an upper and lining, spaced apart means which is inserted between the sole and said upper and lining when placed in position upon said support, stapling mechanism including a staple guide which is adapted to enter between said spaced apart means for the stapling operation and form a part of two folds, means associated with said staple guide to engage the upper and lining on the outside of said spaced apart means to complete the formation of said folds before the staple is driven, and other means associated with the staple guide to draw down the upper and lining over the toe of the last and stretch them before the staple is driven, thereby preventing the upper and lining from receding and later pulling on the peripheral sole portion.

4. A stapling machine having means to support the peripheral portion of a shoe sole on a last also carrying an upper and lining, spaced apart means spaced from the support to enable positioning the sole therebetween and the support while the upper and lining are positioned over said means, a staple guide adapted to enter the space between said means and press the upper and lining against the sole, means enabling lateral yielding of said means to accommodate varying thicknesses of uppers and linings, means associated with the staple guide to contact the leather and draw it and the lining around said spaced-apart means to form folds on the edge of the upper and lining, and means associated with

the staple guide and fold-forming means also engaging the upper to draw the upper tightly over the toe of the last.

5. A stapling machine comprising mechanism by which staples are inserted in the upper, lining and sole of a shoe, means upon which the peripheral portions of the upper, lining and sole are supported preparatory to the stapling operation, and means constituting part of the stapling mechanism and said supporting means co-acting by engagement prior to the insertion of a staple to form folds in the periphery of the upper and lining.

6. A stapling machine comprising means for supporting the peripheral portions of a shoe upper structure, means to support the peripheral portions of a sole in spaced relation to said upper structure portions, and means including a staple guide to press the upper structure toward the sole to form folds around said upper structure supporting means.

7. In combination with the stapling brackets and guide of a stapling machine, means spaced from the brackets to enable the insertion of the peripheral portion of a sole, the upper leather and lining being applied on top of said means, means mounting the aforesaid means in spaced-apart relation to admit the staple guide therebetween for pressing down the upper and lining and driving a staple, means on each side of the staple guide co-operating therewith and with said spaced-apart means to form folds, and other means associated with the staple guide to draw the upper and lining down tightly over the toe of a last by which they are carried, all before the staple is driven.

8. In combination with the stapling bracket and guide of a stapling machine, fingers spaced from the bracket to enable insertion of the peripheral portion of a sole, means spacing the fingers apart to enable entrance of the staple guide to press an upper and lining applied above the fingers into contact with the sole preparatory to driving a staple, means associated with the staple guide to move down outside of the fingers to bear the upper and lining down and form folds, and other means associated with the staple guides to contact the upper in front of the fingers to draw the upper and lining tightly over the toe of a last by which they are carried.

9. In combination with the stapling bracket and guide of a stapling machine, a pair of fingers, means supporting said fingers in spaced relation to the bracket to admit the peripheral portion of a sole and in spaced relation to themselves to enable the staple guide to press an upper and lining down between into contact with the sole, means mounted on each side of the

staple guide to press the upper and lining down on the outsides of the fingers and form folds, and other means associated with the staple guides to press the upper and lining down in front of the fingers.

10. In combination with the stapling bracket and guide of a stapling machine, a pair of fingers, plates to support the fingers in spaced relation to the bracket to enable

10 insertion of the peripheral portion of a sole and in spaced relation to themselves to enable the guide to press an upper and lining down between the fingers in contact with the sole, side wipers associated with the

15 guide to move down outside of the fingers and bear the upper and lining down to form folds, and a fold controller associated with the guide adapted to bear the upper and lining down in front of the fingers.

20 11. In combination with the stapling bracket and guide of a stapling machine, a pair of fingers, a plate applied to each side of the bracket carrying the fingers in spaced relation to the bracket to enable insertion of

25 the peripheral portion of a sole and in spaced relation to themselves to admit the guide for pressing a lining and upper upon the sole preparatory to guiding a staple, side wipers associated with the guide to

30 press the lining and upper in contact with the sole outside of the fingers and form folds, and a fold controller in front of the guide to press the lining and upper into contact with the sole in front of the fingers.

35 12. In combination with the stapling bracket and guide of a stapling machine, a pair of fingers, plates mounted on the sides of the support to hold the fingers in spaced relation to the support for the insertion of

40 the peripheral portion of a sole, and in spaced relation to each other to enable entrance of the guide to press a lining and upper against the sole between the fingers, means in connection with the fingers en-

45 abling yielding thereof according to varying thicknesses of linings and uppers, side wipers associated with the guide having a degree of resiliency to enable them to press the lining and upper down outside of the

50 fingers at all variations thereof, and a fold controller also associated with the guides to press the lining and upper down to the sole in front of the fingers.

55 13. In combination with the stapling support and guide of a stapling machine, a pair of fingers, means to which the fingers are attached holding them in spaced relation to the support to enable the insertion of the peripheral portion of a sole and in spaced

60 relation to each other to permit the guide to press the edge of an upper and lining into contact with the sole between the fingers, means in connection with the fingers en-

65 abling lateral yielding thereof, said means comprising a stem common to both fingers

having means on the ends to adjust the tension of interposed springs, wipers disposed at the sides of the guide having some resiliency to enable adjustments to variations in the positions of the fingers and bear the

70 upper and lining down on the outside into contact with the sole, and a fold controller disposed in front of the guide to press the upper and lining into contact with the sole in front of the fingers.

75 14. In combination with the stapling support and staple guide of a stapling machine, a pair of fingers spaced vertically from the support to enable insertion of the peripheral portion of a sole and spaced laterally to

80 permit the guide to press the edge of an upper and lining between the fingers into contact with the sole, means associated with the

guide to move over the outsides of the fingers to form folds, means in front of the

85 guide to engage the upper leather in front of the fingers and stretch the lining and upper leather, means enabling adjustment of the fingers forwardly to lengthen the fold, means to adjust the side engaging means, 90 forwardly to correspond, means to adjust the fingers upwardly to make larger folds, and means to adjust the aforesaid stretching means in accordance with the other afore- 95

100 15. The combination in a stapling machine of a support for the peripheral edge of a sole, a pair of fingers extending forwardly over the sole and supporting an upper leather and lining preparatory to a

105 stapling operation, plates supporting the fingers, means incorporated in the plate supporting means enabling adjustment of the fingers forwardly to lengthen folds formed in said stapling operation, and means to adjust the fingers upwardly to enable making larger folds.

110 16. The combination in a stapling machine, of a support for the peripheral edge of a sole, lasting fingers extending forwardly of the support and over the edge of said sole, plates at the sides of the support maintaining the fingers in spaced relation to themselves and to the sole support, and means carried by the support forming a

115 bridge under the fingers to relieve them of the strain of a subsequent stapling operation upon the sole.

120 17. In combination with the driving head and staple guide of a stapling machine, means situated on each side of the staple guide to follow the guide to form folds preparatory to a stapling operation, means in front of the staple guide to stretch the leather in said fold-forming act, and means by which the side and front means are carried and by which they are supported upon the driving head.

125 18. In combination with the driving head and staple guide of a stapling machine,

130 means situated on each side of the staple guide to follow the guide to form folds preparatory to a stapling operation, means in front of the staple guide to stretch the leather in said fold-forming act, and means by which the side and front means are carried and by which they are supported upon the driving head.

wiper arms situated at the sides of the staple guide, a fold controller situated in front of the staple guide, means forming the support of the side wipers and fold controller on the driving head, means for adjusting the fold controller on said supporting means axially of the staple guide, and means securing the side wipers both to the

support and the driving head and having associated means enabling axial adjustment 10 of the side wipers in respect to the support and also enabling outward adjustment of the support in respect to the driving head, then carrying said side wipers and fold controller therewith.

ADAM HENRY PRENZEL.
